UNITED STATES PATENT OFFICE

105,210

DESIGN FOR A DUPLICATING MACHINE

Noël Dunbar, New York, N. Y., assignor to The Neison Corporation, New York, N. Y., a corporation of New York

Application April 7, 1937, Serial No. 68,609

Term of patent 14 years

To all whom it may concern:

Be it known that I, Noël Dunbar, a citizen of the United States, residing in New York, county of New York, State of New York, have invented a new, original, and ornamental Design for Duplicating Machine, of which the following is a specification, reference being had to the accompanying drawing, forming part thereof, in which:

Figure 1 is a perspective view of the duplicating machine showing my new design; and Fig. 2 is a plan view of the same.

I claim:

The ornamental design for a duplicating machine, substantially as shown.

NOËL DUNBAR.
